UNITED STATES PATENT OFFICE.

JEAN BAPTISTE NOLIN, OF MONTREAL, CANADA.

DESIGN FOR A BADGE.

SPECIFICATION forming part of Design No. 35,936, dated June 10, 1902.

Application filed January 11, 1902. Serial No. 89,388. Term of patent 14 years.

To all whom it may concern:

Be it known that I, JEAN BAPTISTE NOLIN, a subject of the King of England, residing in the city and district of Montreal, in the county 5 of Hochelaga, Province of Quebec, Canada, have invented and produced a new and original Design for a Badge; and I do declare the following to be a full, clear, and exact description of the same, reference being had to 10 the accompanying drawing, forming a part thereof.

My design is made in flat form in the shape of a Greek cross *a*, having upon the outer end of each arm semicircular or segmental 15 beads *b*. The cross is surrounded just within its edge by a heavy and a light border *d* and *e*, respectively, and the interior space within this border is occupied by a heart *f* in the center of the cross, traversed by a chain of three

links *g*, and surmounted by a fan-shaped ornament resembling the leaves of a plant, and from the center of the ornament *h* there rises a small cross *i*, which is in the form of a Roman cross, centrally located with respect to the upper limb of the large cross. The entire central ornament thus described is surrounded by a series of rays *k*, and the other three limbs of the cross not filled by said ornament afford space for any suitable motto.

What I claim is—

The design for a badge as herein shown and described.

Signed at Montreal this 8th day of January, 1902.

JEAN BAPTISTE NOLIN.
